J. B. SMITH,
MEANS FOR PROMOTING COMBUSTION,
APPLICATION FILED JAN. 15, 1919.
1,353,432.

Patented Sept. 21, 1920.

Inventor:

John Budd Smith

UNITED STATES PATENT OFFICE.

JOHN BUDD SMITH, OF SOUTH ORANGE, NEW JERSEY.

MEANS FOR PROMOTING COMBUSTION.

1,353,432.

Specification of Letters Patent. Patented Sept. 21, 1920.

Application filed January 15, 1919. Serial No. 271,271.

To all whom it may concern:

Be it known that I, JOHN B. SMITH, a citizen of the United States, residing at South Orange, in the county of Essex and 5 State of New Jersey, have invented certain new and useful Improvements in Means for Promoting Combustion, of which the following is a specification.

The present invention relates to improvements in means for promoting combustion. It is generally known and well understood that in the operation of stoves and furnaces, to which my improvement is particularly directed, combustion is incomplete. Various forms of devices have become known by 10 which more complete combustion is obtained. My invention relates particularly to that class of devices which are associated with a flue or stove pipe and serve the purpose of preheating air and distributing it in 15 heated condition into the body of gases passing through the flue or pipe to promote a secondary combustion.

It is the principal object of this invention to provide a device of the character referred to which is exceedingly simple in construction and operation, which can be manufactured at a low price and which is universally adaptable.

Broadly stated my invention consists in 20 an arrangement whereby a minimum length of pipe section is used for preheating the air to the required temperature.

In its more specific aspect the invention 25 consists in means for passing the air to be heated through a heat zone adjacent the pipe circumferentially thereof instead of longitudinally thereof.

The objects and the principle of operation 30 will be more clearly stated in the specification and the characteristic features more particularly pointed out in the claims.

For a fuller understanding reference is 35 had to the accompanying drawings, in which—

Figure 1 is a central section through a length of stove pipe embodying my invention; and

Fig. 2 a similar section showing the preferred embodiment of the invention.

In Fig. 1 10 represents a pipe section of short length and adapted to be connected to the usual outlet nipple of a stove or other pipe section.

Ordinarily a plurality of stove pipe sections of various lengths are combined to

form a pipe flue for passing the products of combustion to the chimney. The section 10 is purposely made of short length so that it may be conveniently inserted at any desired 60 point of a flue.

Along the inner surface of the section 10 is disposed a narrow tubular element 13 defining with the wall of the pipe section 10 an air chamber 11. One or more openings 12 in the wall of the pipe section 10 admit air to this air chamber and perforations 14 in the wall of the tubular element 13 afford a communication between the air chamber 65 and the interior of the pipe section. 70

The air chamber 11 is exposed to the hot gases and the flames and is thereby intensely heated. The cold air enters the air chamber through the opening or openings 12 and passes through the air chamber and the perforations 14 into the flue. The perforations 14 are preferably disposed opposite the opening 12. 75

The air chamber 11 is so constructed that normally a definite quantity of air is heated 80 to a high temperature, the quantity of air with its complement of oxygen being determined by the size of the stove or furnace, the nature of the fuel etc. or rather by the volume per unit of time of unburned products of combustion normally passing out 85 through the pipe.

The highly heated air enters the flue or the fire box and readily reacts upon the products of combustion therein without materially affecting the draft. 90

Fig. 2 shows metal tubes 21 and 23 extending along the inner and outer surfaces of the pipe section 20 respectively. One or more openings 25 in the wall of the outer tube 23 admit air to the outer chamber 24; one or more openings 26 in the wall of the pipe section 20 admit the partly heated air to the inner chamber 22 and perforations 27 in the wall of the inner tube 21 distribute the air into the interior of section 20. The total distance which the air has to travel is thus nearly equal to the circumference of the pipe section 20. If the pipe section 20 has a diameter of 6 inches, the air is brought 95 into contact with a heated strip approximately 18 inches long. 105

While I have found that the embodiments disclosed give complete satisfaction in practice, I do not intend to limit myself thereto. 110 The principal idea of passing the air around the heated walls of the pipe circumfer-

tially thereof may be carried out in various other ways. The length of the circumferentially disposed air chamber may be varied to suit particular requirements. For instance in place of a single annular air chamber a plurality of such chambers may be provided, suitably inter-connected by communicating passages so that the total length of the heated surface with which the air is brought into contact is correspondingly increased.

By making the air chamber spiral in form, the length thereof may be increased to any desired extent.

For these reasons the term "circumferential" is intended to include all air chambers prescribing for the air to be heated, a course which has a circumferential component.

In practice the relation between the nipple of a stove and the opening connecting the pipe to the chimney is often such that a pipe section of the ordinary length is not available for attachment to the nipple. Since the length of pipe section embodying my invention may be reduced to a minimum, it is of substantially universal application.

While my invention has been illustrated and described in connection with a stove, it is obviously applicable to all combustion chambers which are connected by a smoke pipe with a flue or chimney.

In the claims the term "short" is intended to have reference to a length equal to the width of the air chamber and small end portions just sufficient to make connection to adjoining pipe sections.

I claim:

1. As an article of manufacture, a pipe section adapted to form a part of a duct for leading away the products of combustion from a combustion chamber, and a narrow tubular element extending circumferentially along the inner surface of the pipe section and defining therewith an air chamber, the walls of said air chamber being perforated at points remote from each other for admitting air to the chamber and for connecting the chamber with the interior of the pipe section, respectively.

2. As an article of manufacture, a pipe section adapted to form a part of a duct for leading away the products of combustion from a combustion chamber, and means extending circumferentially along the outer surface of the pipe section and defining therewith a narrow air chamber, means extending circumferentially along the inner surface of the pipe section and defining therewith an air chamber narrow lengthwise of the pipe, the outer chamber having an air inlet and the inner chamber communicating at one end with the outer chamber and at the other end with the interior of the pipe.

3. As an article of manufacture, a pipe section adapted to form a part of a duct for leading away the products of combustion from a combustion chamber, means extending circumferentially along the outer surface of the pipe section and defining therewith a relatively narrow air chamber, means extending circumferentially along the inner surface of the pipe section and defining therewith a second relatively narrow air chamber, the outer wall of the outer chamber having an opening to admit air thereto, the wall of the pipe section being perforated at a point substantially diametrically opposite said first opening to admit air into the second air chamber and a plurality of spaced openings remote from the second opening for admitting air from the second air chamber into the interior of the pipe section.

4. As an article of manufacture, a short pipe section adapted to form a part of a duct for leading away the products of combustion from a combustion chamber, and a narrow tubular element extending circumferentially along the inner surface of the pipe section and defining therewith an air chamber, the walls of said air chamber being perforated at points remote from each other for admitting air to the chamber and for connecting the chamber with the interior of the pipe section, respectively.

In testimony whereof, I affix my signature.

JOHN BUDD SMITH.
